(57) **CLAIM**

The ornamental design for a parking brake control valve button cover, as shown and described.

DESCRIPTION

FIG. 1 is a perspective view of a parking brake control valve button cover showing the new design;
FIG. 2 is a top view of the button cover of FIG. 1;
FIG. 3 is a side view of the button cover of FIG. 1;
FIG. 4 is a bottom view of the button cover of FIG. 1; and,
FIG. 5 is a perspective view of the button cover of FIG. 1
engaging a parking brake control valve button.
The broken lines shown in FIG. 5 are for illustrative
purposes only and form no part of the claimed design.
